UNITED STATES PATENT OFFICE.

PETER KRUSE, OF NEW YORK, N. Y., ASSIGNOR TO E. W. BLISS COMPANY, OF BROOKLYN, NEW YORK, A CORPORATION OF WEST VIRGINIA.

SHEET-METAL-WORKING MACHINE.

1,081,050.

Specification of Letters Patent.

Patented Dec. 9, 1913.

Application filed February 24, 1913. Serial No. 750,347.

To all whom it may concern:

Be it known that I, PETER KRUSE, a citizen of the United States, residing in the borough of Brooklyn, county of Kings, city 5 and State of New York, have invented certain new and useful Improvements in Sheet-Metal-Working Machines, of which the following is a specification.

This invention relates to sheet metal 10 working machines and aims to provide certain improvements therein.

An improved hopper for containing sheets of metal to be fed to the machine, improved means for feeding sheets of metal 15 one at a time from the hopper, and improved means for feeding the sheets of metal from one position to another through the machine, are provided by the present invention. Other improvements will herein- 20 after appear.

An embodiment of the invention is shown in the accompanying drawings.

The invention has been shown as incorporated in a machine for making can bodies. 25 The invention may, however, be otherwise embodied and otherwise applied.

In said drawings—Figure 1 is a top plan view of so much of a body making machine as is necessary to illustrate the invention; 30 Fig. 2 is a side elevation of the construction shown in Fig. 1, with the parts in section; Figs. 3 and 4 are respectively a vertical sectional view and a top plan view of parts illustrating the improved feed; Fig. 5 is a 35 side view of the hopper; Fig. 6 is an end view of the horn and its support; and Fig. 7 illustrates a detail of the horn.

In said drawings the letter A designates a suitable table or bench forming the frame 40 of the machine.

B B are a plurality of feed bars working in suitable guide-ways in the top face of the table A, preferably attached to a slide block or piece C, and adapted to be reciprocated by suitable means, as for instance a train of links and levers b¹, b², b³ connected to a crank pin b⁴ upon a disk b⁵ mounted upon a main drive shaft D. The feed bars B B are provided with a plurality 45 of feed fingers, certain or all of which, as for instance the fingers E, may be formed so as to take a positive hold upon or grip sheets of metal X with which they are brought in contact. Other feed fingers E¹

may be provided if desired where the sheets 55 of metal are fed to an idle position.

The grip fingers E (see Figs. 3 and 4) preferably comprise two arms e e¹ which are normally pressed together and which have a narrow slit or opening e² at their 60 forward ends adapted to admit the edge of a sheet of metal. The resiliency of the arms causes them to press upon and firmly grip the sheet of metal. The arms are slightly spread apart by the entrance of the sheet. 65 The ends of the arms e e¹ adjacent the slit e² are preferably rounded or beveled as at e³, to facilitate entrance of the sheet. A screw e⁵ is preferably provided for limiting the spreading apart of the arms e e¹ to prevent 70 breakage, as when a jam occurs and the grip fingers come into contact with two or more superposed sheets. The arms E are pivoted upon the feed bars B as at e⁶ and are adapted to be depressed, against the 75 pressure of a spring e⁷, as they move rearwardly, being so depressed by the sheets of metal with which they come in contact.

F¹, F² and F³ designate a plurality of mechanisms by which the sheets of metal 80 are worked upon. In the construction illustrated, the mechanism F¹ is a notching mechanism for forming notches in the sides of the sheets of metal, the mechanism F² is a flanging mechanism, by which flanges 85 or hooks are formed on the notched sides of the sheets, and F³ is a body-forming mechanism comprising a horn G around which the sheets are bent and the ends interlocked and joined in well known 90 manner. The function of the feed mechanism is to feed the sheets of metal to an exact position with respect to these several mechanisms and that the ends of the sheets and the notches therein shall properly match when wrapped around the horn and the ends joined.

100 Sheets of metal are fed to the machine in any suitable manner (by hand if desired) and are carried forward by the feed fingers upon successive reciprocations of the feed bars B B. As the feed fingers E move into 105 engagement with a sheet of metal the edges of the sheet are gripped by the fingers and the sheet carried forward beyond stops H¹,

22

H^2 and H^3 (see Figs. 3 and 4) mounted upon a fixed part of the machine. As the feed fingers E move back they carry the sheet of metal with them. When, however, 5 the sheet of metal comes in contact with the stops it is stripped from the fingers E and comes to rest at a fixed position determined by the stops. The stop H^1 is herein shown as a gravity finger pivoted upon the sides 10 of fixed portions of the notching mechanism F^1 and operating to lift as a sheet of metal is pushed beneath the same, and to drop behind the sheet as soon as the sheet has pressed beyond them. The stops H^2 15 and H^3 may be pivoted in the frame of the machine and be pressed upwardly into operative position by springs h bearing against their undersides. The stops H^2 and H^3 are depressed by the sheets as they are 20 pushed over them by the feed fingers, and rise to engage the rear edges of the sheet as soon as the sheet has passed beyond them. Strips b^7 are preferably provided, which are adapted to bear upon the upper sides 25 of the sheets X and engage them with slight friction, sufficient to enable the feed fingers E to grip the sheets, but not enough to strip the sheets from the feed fingers on the backward movement thereof.

30 The machine preferably comprises a hopper I in which the lowermost sheets are adapted to be successively separated from those above them by suitable mechanism J to be engaged by fingers b^1 on the feed bars 35 B and fed from the hopper at successive reciprocations of the feed bar. The hopper I comprises two side pieces or plates i constituting lateral guides for the side edges 40 of the sheets of metal. Extending across the tops of the plates i is a cross-piece i^1 having a depending arm i^2 connected thereto at about its middle point. This arm constitutes a guide for the front edges of the 45 sheets of metal. The arm i^2 is adjustably connected to the cross-piece i^1 so as to be adjusted for sheets of various lengths. The plates i are provided at their inner sides 50 with strips i^3 which are adapted to engage, and constitute a guide for, the rear edges of the sheets of metal. These strips i^3 are 55 adjustable longitudinally of the hopper, so as to be adjusted to sheets of different lengths. Plates i^5 are attached to the lower ends of the side plates i and constitute the bottom of the hopper. The lower plates i^5 are spaced apart transversely of one another so as to leave a central space through which 60 the separating mechanism J may obtain access to the under side of the lowermost sheet in the hopper and bend it away from the sheets above, so as to be in position to be engaged by the fingers b^1 on the feed bars and be fed from the hopper. The plates i^5 are 65 adjustably connected to the side plates i so 70 that the transverse distance apart of the

plates may be adjusted and the amount of sag of the sheets of metal in the hopper thereby regulated.

The separating mechanism preferably comprises a vacuum cup or sucker j carried by a reciprocating cross-head j^1 actuated by an eccentric j^2 receiving motion from a drive shaft D^1 through a suitable train of gears j^2 j^3 j^4 . The suction is produced in the vacuum cup j by means of a suitable vacuum pump j^5 driven from the shaft D^1 and connected to the vacuum cup by means of a flexible tube j^6 . The vacuum may be broken by the uncovering of a port j^7 by the piston of the pump at about the time the finger b^1 80 on the feed bars engages the separated sheet, and thus release the sheet from the action of the vacuum cup.

With the present feed, it is desirable to lift the horn during the feeding of the sheets in order that the sheets may not be stripped from the feed finger E^1 by the under side of the horn. For this purpose the horn is mounted upon a slide g working in suitable guides upon one side of a bridge 90 piece L spanning the central part of the machine, and is normally pressed downward by a strong spring g^1 mounted in a suitable part g^2 connected to the bridge L . The slide g is preferably provided with an arm 95 g^3 extending across the bridge piece and is adapted to be engaged by a slide f working in suitable guides upon the other side of the bridge piece and carrying presser feet f^1 forming part of a suitable mechanism, as 100 for instance the flange forming mechanism F^2 . The slide f receives its motion from the drive shaft D through suitable mechanism, as for instance the train of links and levers f^2 , f^3 and f^4 and the cam f^5 on the drive 105 shaft D and acts to lift the slide g carrying the horn G . The amount of lift on the slide g exerted by the slide f may be regulated by means of a screw f^7 on the arm g^3 adapted to come in contact with the top of the slide f . When not lifted by the slide f , the slide g is pressed downwardly by the spring g^1 and causes the horn carried thereby to act as a presser foot upon a sheet of metal beneath the same.

110 In order to hold the sheet against lateral displacement while the horn is lifted, and during the interval between the stripping thereof from the feed fingers and the clamping thereof by the horn, (the sheet during 115 this interval being unsupported at its sides) the horn is provided at its under side with a longitudinal recess within which is fitted a longitudinal strip g^6 , (Figs. 6 and 7) 120 preferably pressed downwardly by light 125 springs g^7 bearing against its upper side. When the horn is lifted, the strip is pressed downwardly by its own weight and the pressure of the springs g^7 against the upper side 130 of a sheet X which is fed beneath the same.

The pressure of the strip g^6 upon the sheet is not however sufficient to cause it to strip the sheet from the feed fingers as the feed fingers draw the sheet rearwardly against the stops H^3 . The end g^8 of the strip g^6 is preferably rounded to facilitate entrance of the sheets of metal beneath the same.

The upper side of the table or bench A is provided at each side with transversely adjustable plates M M. These plates are adjustable by means of hand wheels and feed screws m at each side of the machine. Parts of the mechanisms F^1 and F^2 are carried by these side plates M and are adjustable there- with to adapt the mechanisms to work upon sheets of different widths. The plates i of the hopper mechanism I are attached as at m^2 to the ends of the side plates M. By this construction the hopper as well as the mechanisms F^1 and F^2 may be simultaneously adjusted to receive and work upon blanks of different widths.

The operation of the machine is as follows:—A sheet of metal in the bottom of the hopper I is engaged by the vacuum cup F and bent down in its middle. The feed bar which is at this time in its rear position moves forwardly and the projections b^1 thereon engage the upper edge of the sheet of metal and feed it from the hopper. The vacuum is broken at about the same time that the sheet is engaged by the fingers b^1 of the feed bar, thus releasing the hold of the vacuum cup upon the sheets. After being fed out of the hopper, it is engaged at a succeeding reciprocation of the feed bar by the grip fingers E. These fingers exert a positive hold or grip upon the sheet, and carry the sheet back with them on their rear- ward movement against the stops H^1 which strip the sheets from the grip fingers at a certain and definite position with respect to the notching mechanism F^1 . The sheet is notched while at rest in this position. From the notching mechanism the sheet is fed forward to the flanging mechanism F^2 , (through an idle position if desired) being gripped by grip fingers E and stripped by stops H^2 at a fixed and definite position, as took place with respect to the notching mechanism. The sheets are flanged while at rest by the flanging mechanism, and are engaged by the other grip fingers E at a succeeding reciprocation of the feed bar and fed to the body forming mechanism F^3 . As the sheet is fed from the flanging mechanism F^2 to the body forming mechanism F^3 , the horn G is lifted so as to permit the sheet to pass thereunder and be drawn rearwardly by the grip fingers against the stops H^3 which strip them from the grip fingers, and at a fixed and definite position beneath the horn. While the sheet is fed beneath the horn it is held against displacement by the strip g^6 on the under side of the horn which

bears lightly against the upper side of the sheet. The horn thereupon descends upon the sheet and holds it firmly in place. The sheet is then bent around the horn and its flanged sides interlocked and joined in a well known manner. The sheets which are now in the form of can bodies may be removed from the horn in any suitable manner. Successive sheets follow the same course through the machine.

What is claimed is:—

1. In sheet metal working machines, the combination of reciprocatory feeding means adapted to positively grip and advance a sheet of metal, and means for stripping said sheets from the positive grip of said feeding means upon the backward movement of said feeding means.

2. In sheet metal working machines, the combination of reciprocatory feed fingers adapted to positively grip and advance a sheet of metal, and stops adapted to strip said sheets from the positive grip of said feed fingers upon the backward movement of said fingers.

3. In sheet metal working machines, the combination of mechanism adapted to operate upon sheets of metal, a reciprocatory feed bar, fingers thereon adapted to positively grip the sheet of metal and advance it to said mechanism, and means for stripping said sheets from the positive grip of said fingers at a definite position with respect to said mechanism upon the backward movement of said fingers.

4. In sheet metal working machines, the combination of a hopper having bottom plates constituting a bottom support for the sheets of metal in the hopper, said plates being adjustable on said hopper transversely toward and away from one another, whereby the amount of sag of the sheets between the supported ends thereof may be regulated.

5. In sheet metal working machines, the combination of a hopper comprising side plates and adjustable guides for the front and rear edges of the pile of sheets, and bottom plates constituting a bottom support for the sheets of metal in the hopper, said bottom plates being adjustable independently of the side plates transversely toward and away from one another, whereby the amount of sag of the sheets between the supported ends thereof may be regulated.

6. In sheet metal working machines, the combination of transversely adjustable side-plates between which sheets of metal are to be fed, and a hopper, said hopper having side plates mounted upon and adjustable with said first-mentioned side-plates.

7. In sheet metal working machines, the combination of transversely adjustable side-plates between which sheets of metal are to be fed and adapted to support parts of

- mechanism for working upon the sheets, and a hopper, said hopper having side-plates mounted upon and adjustable with said first-mentioned side-plates.
8. In sheet metal working machines, the combination of a hopper having an open bottom, a vertically movable suction cup adapted to move against and bend downwardly a portion of a sheet of metal contained in the bottom of the hopper, and a reciprocatory feed bar adapted to engage said downwardly bent portion of said sheet while said sheet is in the hopper and feed the same out of said hopper.
9. In sheet metal working machines, the combination of a hopper having bottom plates constituting a bottom-support for the sheets of metal in the hopper, said bottom plates being adjustable transversely toward and away from one another, whereby the amount of sag of the sheets between the supported ends thereof may be regulated, a vertically movable suction cup adapted to move against and bend downwardly a portion of a sheet of metal contained in the bottom of the hopper, and a reciprocatory feed bar adapted to engage said downwardly bent portion of said sheet while said sheet is in the hopper and feed the same out of said hopper.
10. In sheet metal working machines, the combination of a horn adapted to press down and hold a sheet of metal in place beneath the same, means for raising said horn to permit sheets of metal to be fed beneath the same, and means attached to said horn for lightly pressing against sheets of metal while the horn is lifted.
11. In sheet metal working machines, the combination of reciprocatory feeding means adapted to grip and advance a sheet of metal, means for stripping said sheets from said feeding means upon the backward movement of said feeding means, and a horn adapted to be lifted during the feeding of the sheets.
12. In sheet metal working machines, the combination of reciprocatory feeding means adapted to grip and advance a sheet of metal, means for stripping said sheets from said feeding means upon the backward movement of said feeding means, a horn adapted to be lifted during the feeding of the sheets, and means lightly pressing against the sheets to hold them in place during the lifting of the horn.
13. In sheet metal working machines, the combination of presser feet adapted to press and hold sheets of metal in position to be worked upon, a horn adapted to be raised and lowered, and adapted to press down and hold a sheet of metal in place beneath the same, means adapted to operate said presser feet, and connections between said presser foot operating means and horn for communicating motion to said horn.
14. In sheet metal working machines, the combination of presser feet, adapted to press and hold sheets of metal in position to be worked upon, a horn adapted to be raised and lowered, and adapted to press down and hold a sheet of metal in place beneath the same, means adapted to operate said presser feet, and connections between said presser foot operating means and horn for communicating motion to said horn, said connections being adjustable for determining the amount of motion transmitted to said horn.
- In witness whereof I have hereunto signed my name in the presence of two subscribing witnesses.

PETER KRUSE.
